his Atty.

UNITED STATES PATENT OFFICE.

GEORGE WILSON, OF WESTMINSTER, ENGLAND.

PUMP.

SPECIFICATION forming part of Letters Patent No. 243,744, dated July 5, 1881.

Application filed July 13, 1880. (No model.) Patented in England November 20, 1879.

To all whom it may concern:

Be it known that I, GEORGE WILSON, of Parliament Street, in the city of Westminster, England, have invented an Improved Apparatus for Forcing or Raising Water, and also for other purposes, (for which I have obtained a patent in Great Britain, No. 4,733, bearing date November 20, 1879,) of which the following is a specification.

10 My invention consists of a wheel inclosed in a casing and capable of being rotated by steam or other power, this wheel and casing being so arranged that there is a cavity or channel (or cavities or channels) between the periphery of the wheel and casing, this water-passage between the wheel and casing extending partly but not completely around the wheel, and communicating at one end with a supply pipe or conduit and at the other end 15 with an exit pipe or conduit, as more particularly hereinafter described.

The apparatus consists of what I term a "wheel having a cavity or cavities sunk in and extending around its periphery." The transverse section or sections of the said cavity or cavities sunk in the periphery of the wheel may be formed of parabolic, circular, elliptical, or of any other curves, either concave or convex or partly concave and partly convex; or 20 the form may be angular or partly angular and partly curved. The wheel is inclosed and caused to revolve around its axis within an air-tight casing. The flat ends or sides of the wheel revolve close to the sides of the casing; but the portion of the casing inclosing and extending around the periphery of the wheel may be a plain surface or concave or convex, of a circular, elliptical, parabolical, or of any other shape. The suction and discharge of the water 25 respectively to and from the wheel is through a passage or passages in the casing at the periphery. The water flows through the same passages whichever may be the direction the wheel is caused to revolve; but the suction and discharge passages for the water to flow through when the wheel is caused to revolve in one direction respectively become reversed, or discharge and suction passages when the wheel is caused to revolve in the contrary direction.

40 The action of the apparatus is as follows: The air-tight casing inclosing the wheel and also

the suction-pipe being full of water, (in a similar manner to an ordinary centrifugal pump,) the wheel is then caused to revolve by steam or any other power with the requisite velocity in the desired direction, and the action of the cavity or cavities sunk in the periphery of the revolving wheel upon the water causes the latter to be forced by friction, or by friction and suction, round in the direction the wheel revolves, 55 through the apparatus and discharge pipes or passages.

50 My said invention, besides being applicable as a pump for the purpose of lifting or forcing water or other fluids, is also applicable for forcing water out of the stern or other part of a vessel in any desired direction for propelling the same, or out of the side or sides of the vessel for steering the same.

In order that my said invention may be clearly understood, I will now give general illustrations of the same.

55 Referring to the hereinbefore description and to the drawings hereunto annexed, Figures 1 and 2 are sections through the apparatus, in which one cavity is sunk in and extends around the periphery of the wheel. The solid thick black lines show the wheel, which revolves on the axis *g g* on bearings *h h*. *m m* is the casing inclosing the wheel, and *o* is the cavity 60 sunk in the periphery of the wheel.

Fig. 3 is a section of a wheel in which four cavities, *o o*, are sunk in its periphery.

Fig. 4 shows a section of a wheel the cavity or cavities of which are partly angular. Supposing that the wheel is caused to revolve in the direction shown by the arrow *s*, the water will flow through the suction pipe or pipes at *F* and enter tangentially the cavity or cavities of the wheel at *Y'*, and, after being forced through the apparatus by the frictional action of the revolving wheel, the same will enter tangentially at *Y* and be discharged through the pipe or pipes at *G*. If the wheel is caused to revolve in a contrary direction to that hereinbefore lastly described, then *G* becomes the suction and *F* the discharge pipe or pipes for the water. The casing is formed in such a manner, as shown at *Y Y'*, that in either direction in which the wheel is caused to revolve the water forced partly around the casing by the action of the revolving wheel flows tangentially from 70 75 80 85 90 95 100

the suction pipe or pipes into the cavity or cavities of the wheel, and also tangentially from the latter into the discharge-pipe or pipes. The distance between Y and Y'—the tangent-points for the entrance and discharge of the water into and from the cavity or cavities of the wheel—is dependent on the desired arrangement of the suction and discharge pipes with regard to the casing.

- Fig. 5 shows the suction and discharge pipes H J (one of which is shown straight and the other curved) arranged in such a manner that the water will be acted upon by the revolving wheel and forced round the casing through the distance of a semicircle.

The suction and discharge pipes and also the apparatus should be constructed in such a manner as to cause the water to flow in continuous volumes of uniform or nearly uniform sectional areas.

In the application of my improved apparatus as a pump for the purpose of lifting or forcing water or other fluids, one of the pipes, G or F,

would be the suction and the other the discharge pipe for the water, the arrangements 25 being as for ordinary centrifugal pumps. This pump can also be used for propelling or steering vessels by forcing the water from the stern or other part in various ways.

Having thus fully described my said invention and the manner of performing the same, I wish it to be understood that I claim—

My improved apparatus, consisting of a wheel inclosed in a casing and capable of being rotated by steam or other power, the wheel and casing being so arranged that there is a cavity or channel (or cavities or channels) between the periphery of the wheel and the casing, extending partly but not completely around the wheel, and communicating at one end with a supply 35 pipe or conduit and at the other end with an exit pipe or conduit, substantially as described.

GEORGE WILSON.
